UNITED STATES PATENT OFFICE.

PERRY EDWARD ROWE, OF AMARILLO, TEXAS.

TOOL-HANDLE FASTENER.

Application filed September 9, 1926. Serial No. 134,510.

The object is the provision of a means for holding and adjustably securing the head of an implement, such as a hammer or the like, on the wooden handle therefor, the device being characterized by simplicity in construction and reliability and efficiency in practical use.

To the attainment of the foregoing the invention consists in the improvement as hereinafter described and definitely claimed.

In the drawings:

Figure 1 is a side elevation illustrating the application of the improvement.

Figure 2 is a sectional view on the line 15 2—2 of Figure 1.

Figure 3 is a plan view of the sleeve.

Figure 4 is an end view thereof.

Figure 5 is a plan view of the split nut employed.

20 In the drawings I have illustrated my improvement in connection with a machinist's hammer but obviously the device is not to be thus restricted in its useful application, as the same may be successfully employed 25 for holding implement heads of any character on wooden handles therefor.

The wooden handle is indicated by the numeral 1, the eye end 2 of which is tapered. Arranged over the end 2 of the handle 1 30 there is a tapered sleeve 3 that provides one of the important elements of the improvement. The sleeve is split longitudinally as clearly disclosed by Figure 3 of the drawings and the outer or reduced end of the 35 sleeve is formed with a reduced outstanding head 4 which is round in plan and which is exteriorly threaded. The inner face of the head 4 is slotted, as at 5, and between these slits there is integrally formed on the said 40 inner face of the head a wedge 6. In arranging the sleeve on the end 2 of the handle 1, the head 4 is subjected to an impact of force such as a blow from a hammer to cause the wedge 6 to be inserted in the said end 2 45 of the handle. By reference to the drawings it will be noted that the inner bore of the sleeve is tapered, as at 7, and the end of the handle divided by the wedge 6 is forced into this tapered portion of the bore, thereby ef- 50 fectively securing the sleeve on the end of the handle. The sleeve 3 is inserted in the usual manner through the eye of a hammer or like implement 8. The implement 8 is reamed inwardly around the eye or bore thereof from the outer face of the said im- 55 plement. Screwed on the head 4 there is a

split nut 9, and this nut has an inner cone face 10 that contacts with the beveled wall 11 provided by the said reamed part of the implement head. Thus when the nut 9 is 60 screwed home the ends thereof will be forced toward each other and as the nut embodies a natural resiliency and the ends thereof have a tendency to spring away from each other, it will be seen that the nut is effec- 65 tively locked on the implement handle and in engagement with the head of the sleeve.

The simplicity of my improvement and the advantages thereof, will, it is thought, be perfectly apparent to those skilled in the 70 art to which such invention relates when the foregoing description has been carefully read in connection with the accompanying drawings, it being, of course, understood that I do not wish to be restricted to the precise details of construction herein set forth and therefore hold myself entitled to such changes therefrom as fairly fall within the 75 scope of what I claim.

Having described the invention, I claim: 80

1. A means for holding a wooden handle in the eye of an implement, comprising a split sleeve having an outer head which is exteriorly threaded and having an inner wedge that is designed to be inserted in the 85 end of the handle, said sleeve designed to be inserted through the eye of the implement and a nut screwed on the head of the sleeve and partly received in the eye of the imple- 90

95 ment.

2. A means for securing a wooden handle on an implement, comprising a split sleeve having an outer head which is round in plan and exteriorly threaded, said head being slotted on the inner face thereof, a wedge in- 100 tegrally formed on the head between said slits, said wedge designed to be inserted in the end of the handle which is received in the sleeve, said sleeve adapted to be inserted through the eye of the implement, and a split nut screwed on the head of the sleeve and partly received in the eye of the imple- 105 ment and contacting with the wall provided thereby.

3. A means for securing a wooden handle on a hammer or like implement, and in which the wooden handle has a tapered end, said means including a split sleeve, which is tapered and which has its reduced end formed with a head extension, the latter be- 110 ing round in plan and having exterior teeth, the bore of the sleeve being tapered for a

distance from its juncture with its head, said head having its inner face slotted and being formed with a rearwardly extending wedge between said slits, said wedge adapted to be inserted in the mentioned end of the handle to spread said end to contact with the bore of the sleeve, the outer face of the hammer head being beveled around its eye and the

sleeve adapted to be inserted through said eye and a split nut screwed on the head of the sleeve and having an inner cone face received in and contact with the eye of the hammer head.

In testimony whereof I affix my signature.

PERRY EDWARD ROWE.
